DESIGN FOR A HANDLE FOR SPOONS, &c.

Design No. 20,427, dated December 23, 1890.

UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A HANDLE FOR SPOONS, &c.

SPECIFICATION forming part of Design No. 20,427, dated December 23, 1890.

Application filed November 17, 1890. Serial No. 371,742. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for Handles of Spoons, Forks, Knives, Ladles, &c., of which the following is a specification, reference being had to the accompanying illustrations, forming part thereof.

Figure 1 is a photographic illustration of the obverse or front face of a spoon-handle, and Fig. 2 is a similar illustration of the reverse or bottom face of the same.

My design for the obverse face consists of a raised fan-shaped ornament *a* at the wide end of the spoon-handle, with a raised marginal ornamentation running down to the shank and consisting of a series of raised knobs or heads *b* and inwardly-projecting

tongues *c c'*, an enlargement *d* between the shank and the spoon-bowl being also ornamented with raised tongues and a central scroll. The back or reverse side of the handle is perfectly plain, with the exception of a fan-shaped ornament *e* in relief at the wide end of the handle. 25

What I claim is—

1. The design for the obverse or front side of the handle, as herein shown and described. 30
2. The design for the handles of spoons, &c., consisting of the raised ornamentations *a*, *b*, *c*, *c'*, and *d* upon the front side and the raised ornament *e* upon the back side, as herein shown and described.

AUSTIN F. JACKSON.
